UNITED STATES PATENT OFFICE.

CYRUS KEHR, OF CHICAGO, ILLINOIS, ASSIGNOR TO ROBERT S. WILLIAMS AND CHARLES H. ROBERTS, BOTH OF SAME PLACE, AND JOHN G. MANAHAN, OF STERLING, ILLINOIS.

MACHINE FOR TURNING IRREGULAR FORMS.

SPECIFICATION forming part of Letters Patent No. 372,806, dated November 8, 1887.

Application filed May 27, 1886. Serial No. 203,466. (No model.)

To all whom it may concern:

Be it known that I, CYRUS KEHR, a citizen of the United States, residing at Chicago, in the county of Cook and State of Illinois, have invented certain new and useful Improvements 5 in Machines for Turning Irregular Forms; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 My invention relates to machines for turning irregular forms, and has more especial reference to that class of such machines in which an exterior surface is fitted to be received by a cavity, the walls of such cavity guiding the knife 20 of the machine in the process of turning.

The invention is shown herein as applied 25 to turning the ends of wagon-axles to receive their skeins. The interior of these skeins is oval, ovate, or irregular in cross-section, and the degree of departure from a circular cross- 30 section varies at different points along the length of the skein, and the mean diameter of the skein also increases from its inner to its outer end. Consequently provision must be made for a constant variance in the path of 35 the knife corresponding to the irregularities in the interior of the skein, irregularities on the interior of the skein being produced in reverse on the exterior of the axle. Heretofore 40 this work has been done successfully in only one mode—namely, by the use of a machine having a cutter-bar pivoted at its center and rotating in a direction transverse to the plane of oscillation and progressing longitudinally 45 as it rotates, one end thereof acting as a tracer upon the inner wall of the stationary skein and the other bearing the knife and rotating around the end of the fixed axle and cutting it down to the required form, said knife and said tracing end being, when the machine is 50 in operation, on opposite sides of and in a line extending diagonally through the axis of rotation. During the operation of cutting

said cutter-bar has heretofore been caused to progress by means of a screw.

The differences between my machine and that mentioned above will appear from the following description.

In the accompanying drawings, Figure 1 is 55 a plan of the machine. Fig. 2 is a section in line $x x$ of Fig. 1. Fig. 3 is a plan with the carriage removed. Figs. 4 and 5 are detail views of the cutter-bar and cylinder.

A is the frame of the machine, which is provided at its sides with the parallel inwardly-directed tongues A' A'. B is a sliding carriage having channels B' at its sides, into which the tongues A' fit. Said carriage has an opening, B², at its middle, and at each end a bearing, B³, to receive the trunnions C' of 65 the cylinder C. Said cylinder C is hollow and open at its ends, and its outer surface is provided over its entire length, between its bearings, with continuous longitudinal cogs.

D is the cutter-bar. This is arranged within 70 the cylinder C, parallel with the axis of the latter and suspended from a hinge, D', at one side of and parallel with said bar and the axis of the cylinder, the bar being thus allowed to oscillate in a direction perpendicular to its own axis and that of the cylinder, but at all times held in a position parallel to its own axis and the axis of the cylinder.

To make the connection between the main portion of the cutter-bar and the hinge D', 80 the bar may be deflected laterally along its middle to lie in the line of the hinge, as shown in Fig. 5; or the bar may be straight and have the transverse arms D² D² extending outwardly to the hinge D', as in Fig. 4. In Figs. 1, 2, 85 and 4 I show the hinge formed at the outer end of two transverse arms, C', seated on the outer ends of the trunnions C. These arms are used in order to provide a relatively longer radius for the oscillations of the cutter-bar. 90

A spring, D³, may be seated within the cylinder C to press the bar D outwardly from the center of the cylinder, so as to hold the tracer against the wall of the skein before that office is performed by the axle-blank through the 95 engagement of the latter with the knife.

D⁴ is the tracer, and D⁵ the knife, the latter being directed toward the axis of revolution, and one being on the same side of and as far from the axis of the cylinder C as the other is; 5 or, in other words, both are in a line parallel to the axis of said cylinder, rather than on opposite sides of and in a line extending diagonally through said axis, as is the case in the form of machine to which reference is 10 made at the beginning of this specification. The dotted lines around the tracer indicate the position of the skein, which is suitably centered and rigidly fixed over the end of the cutter-bar, and the dotted lines at the opposite 15 end of the cutter-bar indicate the end of the axle, which is also suitably centered and fixed.

Now, when the cylinder C is rotated, the entire cutter-bar will revolve in an orbit around the axis of the cylinder, and its distance from 20 said axis will be regulated by the shape and diameter of the interior of the skein. Where the wall of the skein approaches the axis of revolution, the entire bar will be swung toward said axis and the corresponding part of 25 the end of the axle cut deeper, and vice versa. Since the tracer and knife are both on the same side of the axis of revolution, the corresponding sides of the skein and axle must be on the same side of the axis of revolution instead of 30 on opposite sides, as is the case in the form of machine to which reference is made at the beginning of this specification.

Beneath and meshing into the cylinder C is located the spur-gear E, mounted upon the 35 short shaft E', at the opposite end of which is the miter-gear E'', meshing into the miter-gear F on the driving-shaft F'. Said shaft F' is driven by the drive-pulley G or otherwise.

Beneath the carriage B is a transverse shaft, 40 H, bearing the small spur-wheels H' H'', which mesh into racks B⁴ B⁴ on the under side of the carriage B. Said shaft H is driven by the shaft F', through the spur-wheels H² and F².

The rotation of the spur-gear E rotates the 45 cylinder C, while at the same time the carriage B and the cylinder are drawn forward by the wheels H', the cogs on the spur-gear E meanwhile sliding along between the cogs on the cylinder C.

50 The wheel H² is held in engagement with its shaft by the clutch I. When the carriage has been drawn forward as far as desired, said clutch is released and the shaft H rotated in the opposite direction by means of the hand-crank J or otherwise, thus returning the carriage to its original position.

The mechanism for operating the clutch I is as follows: The forked upper end of an arm, L, 55 engages the clutch, while at its middle it is pivoted to a stationary support, L', and at its lower end it is hinged to a horizontal rod, L'', extending to the opposite side of the machine, where it terminates in a ring, l, which embraces an eccentric, M. Said eccentric rotates 60 upon a shaft, N, supported from the frame A of the machine or otherwise. An arm, N',

may be so attached to the eccentric as to hang a little out of a vertical position when the eccentric has driven the rod L'' inward as far as permitted by the clutch I, the weight of said 70 arm N' serving to hold the clutch in engagement. To throw the clutch out of engagement, the arm N' is raised in the direction indicated by the arrow in Fig. 2, and allowed to rest on a support, N'', the eccentric drawing 75 the rod L'' outwardly and throwing the clutch from the wheel H².

It is obvious that the carriage and cylinder may be progressed by only one rack, B⁴, and spur-wheel H', or by a screw or ratchet mechanism. 80

The bearing-surfaces of the tracer and knife of the cutter-bar D must be in the same line parallel with the axis of the cylinder C, and said bar is bent or deflected from said axis 85 sufficiently for that purpose, and such line is to be regarded as the "axis" of the cutter-bar whether the latter is straight or bent, and its axis of oscillation is the hinge D', while its axis of revolution is the axis of the cylinder. This 90 machine may also be used for turning duplicates of irregular or non-cylindrical forms by causing the tracer to traverse the exterior of the pattern, and it may also be used in like manner for reaming from a pattern. 95

I claim as my invention—

1. The combination, with a rotating cylinder, of a cutter-bar passing through said cylinder parallel with the axis of the latter and attached to the cylinder by a hinge located 100 outside of and parallel to the axis of the cylinder, whereby both ends of the cutter-bar may oscillate in unison on the same side of the axis of the cylinder, substantially as shown and described. 105

2. The combination, with a rotating longitudinally-progressing cylinder, of a cutter-bar passing through said cylinder parallel with the axis of the latter and supported by the cylinder from a hinge located outside of and parallel 110 to the axis of the cylinder, whereby both ends of the cutter-bar may oscillate in unison on the same side of the axis of the cylinder, substantially as shown and described. 115

3. The combination, with a rotating cylinder supported on a carriage having a longitudinal movement, of a cutter-bar passing through said cylinder parallel with the axis of the latter and supported by the cylinder from a hinge located outside of and parallel to the 120 axis of the cylinder, whereby both ends of the cutter-bar may oscillate in unison on the same side of the axis of the cylinder, substantially as shown and described. 125

4. The combination of the carriage B, rotating cylinder C, mounted thereon, and cutter-bar D, hinged to said cylinder to oscillate upon an axis outside of and parallel to the axis of 130 said cylinder, substantially as shown and described. 135

5. The combination of the carriage B, a cylinder, C, provided with the cutter-bar D and

having longitudinal cogs extending from one bearing to the other, the stationary spur-wheel E, one or more racks, B', and one or more spur-wheels, H', said spur-wheels E and H' being driven simultaneously, substantially as described.

6. In a machine for turning irregular forms, the combination of a hollow rotating cylinder and a cutter-bar suspended in said cylinder to oscillate upon an axis outside of and parallel to the axis of said cylinder and revolving therewith, such cutter-bar being provided with a tracer at one end and a knife at its opposite end, having their bearing-surfaces in a line parallel to the axis of the cylinder C, and placed in suitable relation to a fixed blank and pattern, substantially as shown, and for the purpose described.

7. In a machine for turning irregular forms, the combination of a hollow rotating cylinder, 20 C, and a cutter-bar, D, the latter being suspended within said cylinder in the walls thereof, and while the machine is in operation having its bearing extremities in a line outside of and parallel with the axis of said cylinder, 25 whereby one end of said bar can be used as a tracer to transmit through said bar the desired direction to the knife, substantially as shown and described.

In testimony whereof I affix my signature in 30 presence of two witnesses.

CYRUS KEHR.
